UNITED STATES PATENT OFFICE

JOHN FACCARO, OF ST. LOUIS, MISSOURI

STRINGED MUSICAL INSTRUMENT

Application filed December 17, 1928. Serial No. 326,473.

This invention relates to improvements in stringed musical instruments and consists of the construction hereinafter disclosed.

The object of the invention is to provide a stringed musical instrument of the general type of a violin comprising a unitary structure in which there is a common neck and peg box connected with a body in which there are formed two sound boxes on reverse sides of a partition in the box resulting in a structure by which a performer may produce different tonal qualities and effects.

The construction of the instrument will be understood by those skilled in the art from the following description taken in connection with the drawing in which—

Fig. 1 is a front elevation of one face of the instrument; and

Fig. 2 is an edge view partially in vertical section showing the construction.

In the embodiment of the invention illustrated in the drawing, the body of the instrument has the general outline or contour of musical instruments of the violin type. The body is formed from two face boards 1 and 2 each of which is provided with the usual sound holes 3. The space between the face boards is divided by a partition 4 coextensive therewith but having an offset position with respect of the median line through the instrument; that is to say, as illustrated in the drawing, the space between the inner face of the member 1 and the partition is somewhat greater than the space between the inner face of the partition 2 and the face of the partition, thereby providing chambers 5 and 6 of unequal volumetric capacity. It is understood that this will result in different tonal qualities. It should also be understood that the tonal qualities of the sounding chambers may be varied by varying the thickness or character of wood from which the members 1 and 2 are respectively made.

To the body of the instrument there is connected a unitary neck 7 having spaced arms 8 and 9; the distance between the arms 8 and 9 forming a space 10 of a sufficient width to permit the insertion of the hand of the performer between the arms. The neck 7 is attached directly to the upper portion of the

body and finger boards 11 and 12 are connected with opposite faces of the neck. Formed integral with the neck is a pair of peg boxes 13 and 14 which terminate in a reversely formed scroll 15.

Each face of the instrument is provided with a separate bridge 16 and 17, respectively.

Separate tail pieces 18 and 19 are connected by a common button 20 to the body and extend on opposite faces thereof.

The strings, given the general reference numeral of 21, are strung on opposite faces of the instrument and may be of a character to produce musical notes of different pitch. Each series of strings is attached to the respective tail pieces 18 and 19, extend across the respective bridges 16 and 17 and are connected at their opposite ends to pegs 22 mounted in the peg boxes 13 and 14; the peg holes in said peg boxes being respectively offset in order to permit ready tuning of the strings without interference with the adjacent pegs.

It is obvious from the foregoing description of the construction that an instrument is provided that has a wide range for solo or orchestral work as well as for special trick stage playing, by which an unusual musical performance can be given with a single instrument.

I am aware that my invention may be modified in certain particulars without departing from the nature and principle thereof; therefore, I do not limit myself in unessential particulars but what I claim and desire to secure by Letters Patent is:

1. A stringed musical instrument comprising the combination of a unitary body, a partition dividing the body into sounding chambers of unequal volumetric capacity; a neck attached to the body provided with peg boxes and pegs for supporting one end of the strings, and a complete complement of strings positioned across the respective sound boxes.

2. A stringed musical instrument comprising a body, an internal partition in the body dividing the body into sound chambers of different depths, a neck attached to the body, and a complete complement of strings strung

across opposite faces of the body and supported at the opposite end at the upper end of the neck.

3. A stringed musical instrument comprising a body, a partition dividing the body into separate sound chambers, a neck connected with the body, having separate arms spaced apart, finger boards supported at opposite sides of the neck above said arms, and a complement of strings attached in a manner to cross the separate faces of the body and to be adjustably connected at their opposite ends at the upper extremity of the neck.

4. A stringed musical instrument comprising a body, a partition dividing the body into separate sound chambers having different tonal producing construction, and a complete complement of strings positioned across the respective sound chambers.

JOHN FACCARO.
